CLAIM

The ornamental design for a stop for the sliding fifth wheel of a large truck, as shown and described.

DESCRIPTION

FIG. 1 is a perspective view of a stop for the sliding fifth wheel of a large truck showing my new design; FIG. 2 is a front elevational view thereof, the rear view being a mirror image of that shown; and, FIG. 3 is a side elevational view thereof, the opposite side and top and bottom views being mirror images of that shown.

FIG.1.

FIG.2.

FIG.3.
